UNITED STATES PATENT OFFICE.

HENRY M. HOBART, OF SCHENECTADY, NEW YORK, ASSIGNOR TO GENERAL ELECTRIC COMPANY, A CORPORATION OF NEW YORK.

COOLING ELECTRICAL APPARATUS.

1,105,783.

Specification of Letters Patent. Patented Aug. 4, 1914.

Application filed November 11, 1913. Serial No. 800,806.

To all whom it may concern:

Be it known that I, HENRY M. HOBART, a citizen of the United States, residing at Schenectady, county of Schenectady, State of New York, have invented certain new and useful Improvements in Cooling Electrical Apparatus, of which the following is a specification.

My invention relates to transformers and particularly to the common water cooled transformers.

The object of my invention is to prevent the condensation of moisture from the air within a transformer tank.

As is well known, changes in the relative temperatures of a transformer and the atmosphere cause exchanges of air between the interior of the transformer tank and the atmosphere, unless, of course, the tanks are made and maintained air tight which is distinctly undesirable in most cases. Each time air enters a tank it tends to convey with it the moisture which may be in suspension in it. This moisture in turn condenses within the tank under certain conditions of temperature relations, with the consequent reduction of the electrical strength of the insulating materials.

In order for moisture to condense out of air it is necessary that the air be cooled below the temperature corresponding to its humidity. I propose to utilize this principle to prevent the condensation of moisture within a tank by cooling the entering air to a temperature lower than that of the transformer tank before the air mixes with the fluid within the tank, and receiving and harmlessly disposing of the moisture which may condense out. It is preferable that this temperature shall be lower than any to which the air may be subjected while within the tank. In water cooled and similar artificially cooled transformers, this cooling of the entering air may be readily accomplished by subjecting it to the effects of the entering cooling fluid. To do this I prefer to surround a pipe conveying the air between the interior of the tank and the atmosphere by a fluid conductor, as a jacket, through which the cooling fluid may flow on its way to the interior of the tank.

The single figure of the drawing illustrates my invention applied to a common form of water cooled transformer.

The transformer tank 1 contains a trans-

former 2 above which is suspended the cooling coil 3. According to common practice, the cooling coil 3 is located below the surface of the oil insulating and cooling the transformer 2 and is constantly supplied with water through the pipe 4, the water flowing out of the coil through the pipe 5. Above the surface of the oil is an air chamber. This air chamber communicates with the atmosphere through the pipe 6. About a vertical portion of the pipe 6 I have placed the jacket 7. The upper end of the jacket 7 is connected to the pipe 4 and the lower end is connected to the pipe 8 of the source of water for the cooling coil.

It will be apparent from this construction that as water flows from the source 8 to the cooling coil, it passes through the jacket 7 about the pipe 6. Any air drawn into the transformer tank passes through the pipe 6. The pipe 6 and the jacket 7 are of such length that the air in its passage through the pipe 6 is cooled, preferably, to a temperature below any to which it will be subjected within the transformer tank and is maintained at this low temperature for a sufficient period of time to allow so much moisture to be condensed out as the air can give up at this temperature. The pipe 6 being vertical and open at its lower end, this moisture condensing on the interior of the pipe 6 flows down the pipe 6 and out at its end. The result of this is that after the air passes through the pipe 6 into the interior of the tank 7 no more moisture will be given up by it so long as it remains within the tank.

It will be understood that this construction is but a simple preferred one involving my invention, particularly applicable to water cooled transformers, and that my invention is not limited to this construction but is defined by the following claims.

What I claim as new and desire to secure by Letters Patent of the United States, is:—

1. The combination with a transformer tank and a transformer therein, of means providing a passageway for the exchange of air between the interior of the tank and the atmosphere and for cooling the air in said passage below the temperature within the tank.

2. The combination with a transformer tank, a transformer and a cooling coil therein and means for supplying a cooling fluid

to said coil, of a pipe providing a passage-way for the exchange of air between the atmosphere and the interior of the tank and a fluid conducting means about said pipe, said fluid conducting means being connected between the cooling fluid supplying means and the cooling coil.

In witness whereof, I have hereunto set my hand this 10th day of November 1913.

HENRY M. HOBART.
